(57) **CLAIM**

I claim the ornamental design for a “transitional pocketbook organizer insert sack,” as shown and described.

DESCRIPTION

FIG. 1 Front View of my new transitional pocketbook organizer insert sack

FIG. 2 Rear View of the transitional pocketbook organizer insert sack

FIG. 3 Top View (opened) of the transitional pocketbook organizer insert sack; and,

FIG. 4 Top View (closed) of the transitional pocketbook organizer insert sack.

My “transitional pocketbook organizer insert sack” is characterized by the many compartments, the frame that allows the sack to remain open until closed, and the chain attached to the rear of the sack.
